United States Patent Office

Des. 230,019
Patented Jan. 22, 1974

230,019

VAN

Donald H. Cox, Lima, Ohio, assignor to Sheller-Globe
Corporation, Toledo, Ohio

Filed Mar. 27, 1972, Ser. No. 338,725

Term of patent 14 years

Int. Cl. D12—08

U.S. Cl. D14—3 J

FIG-2-

FIG. 3

FIG. 4

FIG. 1 is a right side elevational view of the van showing my new design, the opposite side being substantially a mirror image thereof;

FIG. 2 is a top plan view thereof;

FIG. 3 is a rear elevational view thereof;

FIG. 4 is a front elevational view thereof.

I claim:

The ornamental design for a van, as shown and described.
